Attorney

UNITED STATES PATENT OFFICE.

FRANK MIMICK, OF COLUMBUS, NEBRASKA.

CARBURETOR CONSTRUCTION.

Application filed December 4, 1924. Serial No. 753,833.

The invention relates to devices for improving the action of carburetors or vaporizers of hydrocarbon fuels such as are used in the operation of internal combustion motors in vehicles. I am aware that efforts have been heretofore made to improve the function of the charge former by heating the charge including the use of an electrical resistance element exposed in the fuel passage, but such devices have called for special structures involving a considerable departure from accepted designs of carburetors, and it is therefore an object of my invention to present means for utilizing the ordinary carburetor to attain the advantages of a fuel heater in improving the vaporizing functions.

10

15

It is an especial aim of the invention to present a device which may be attached to the ordinary carburetor to heat the fuel therein, without interfering with the functioning of the usual parts found therein.

An important purpose of the invention also, is to attain the improvement in vaporization by an ordinary carburetor in a manner novel in such appliances. That is to say, I propose to warm the entire body of fuel in the bowl of the usual carburetor, whereby the primary mixture conduit walls and jet parts are also warmed and prevented from counteracting the effect sought, in addition to the fuel being brought to a favorable temperature.

25

30

35

A further object is to provide a novel structure in an attachable heater unit suitable for the purpose described, which will involve a minimum of labor for its installation, and will not require high mechanical skill on the part of the person making such installation.

Additional objects, advantages and features of invention reside in the construction, arrangement and combination of parts as may be understood from the following description, and accompanying drawings, in which—

Figure 1 is an elevational view of a carburetor now largely used, my invention being incorporated therein, part of the bowl being broken away to show the heater element within the bowl;

Figure 2 is a view from the left of Figure 1 showing the heater element in cross section and the float of the carburetor in lowermost position;

Figure 3 is a horizontal section of the heater element;

Figure 4 is a fragmentary horizontal section of a modified mounting of the heater element;

Figure 5 is a fragmentary vertical section of a further modification of the mounting of the heater element.

There is illustrated a carburetor comprising the cast body 10 which includes a usual arrangement of the common essential parts in integral form there being a primary mixture element or tube 11 extended downward within the bowl 12, the bottom of which is secured in a familiar way to this extension with the edge of the bowl pressed upon a suitable seat provided upon the plate 13 forming part of the body 10 and enclosing the bowl. Upon the under side of this plate also, a float 14 is pivotally supported, operative to regulate the admission of fuel by the valve 15 as is well understood.

The bowl 12 is the usual plain cylindrical pressed metal cup having a planiform bottom 16 apertured to receive a tenon therethrough by which the nut 17 may clamp the bottom to the element 11. The junction of the bottom and wall of the bowl is usually rounded as at 18, and as my invention requires to be mounted on the lower part of the wall of the bowl, it is an important advantage that I am able to do so without a complicated mounting.

The attachable device in my invention includes a base 20 of insulating material (compressed fiber having been employed), from which a cylindrical core 21 extends, the base having a curved face 22 corresponding to the shape of the inner surface of the wall of the bowl. The chord of this curve subtends the axis of the core at an angle of about 52 degrees in this instance, so that when the base is placed within the bowl and pressed snugly against the side thereof, the core will extend medially between the part 11 and the side of the bowl and obliquely from the part of the bowl wall

abutted. If necessary, the base may be additionally cut away or moulded to conform to the curve 18 of the junction between the bottom and wall of the bowl. Coaxially inserted through the core there is a mounting and terminal bolt 23, having a head 24 against the extremity of the core, and a threaded part 25 projecting through the base a distance. The bolt is preferably rectangular where engaged in the core, and is preferably cemented therein. After insertion, the threaded part of the bolt is bent to extend at right angles to the chord of the curved face 22 as shown in Figure 3. 15 Upon the core 21 there is wound a coil 26 of suitable resistance wire 26 and an asbestos cord 27, the cord being laid between the helices of the wire. One end of the wire is soldered to the head 24, while the other is 20 secured under the head of a screw 28 engaged in the side of the base 20, which screw also retains a light contact spring 29 arranged to bear against the inner surface of the bowl and make secure electrical contact therewith. At the outer threaded part of the bolt 23 a washer 30 of hard insulating material and two nuts 31 are provided.

In attaching this device, it is simply necessary to drill one hole 32 at any point in the bowl immediately above the curved junction of the wall and bottom of the bowl, that is, in a vertical part of the wall as near the bottom as practicable and usually about five-eighths of an inch above the level of the bottom 16; adjust the device within the bowl with the threaded part 25 of the bolt projected through the drilled opening 32, then adjust the washer and nuts, tightening the first of the nuts so as to effect a tight fit of the washer against the bowl. The washer preferably has a boss on the under side to fit within the drilled hole 32 so as to center the bolt and prevent the latter from contacting with the bowl. A wire 33 may be secured under the outer nut, which may be extended from any usual switch and electrical source, one terminal of which would be grounded on the frame of the motor, as is familiar, whereby the wire 26 may be heated when required to warm the contents of the bowl and the submerged parts of the carburetor. In putting the bowl in place after attachment of the device as described, the core and winding must be 55 adjusted at the same side of the body casting 10 with the float pivot and parallel to the axis of the pivot, so that the latter may have full movement to lowermost position without contacting with the coil, as shown in Figure 2.

The parts are illustrated full size as actually constructed ordinarily heretofore, and the parts should be proportioned approximate as shown to enable ready assemblage

and function with adequate marginal allowances for errors or faults in manufacture and installation. 65

With the single bolt mounting described the coil will be held accurately positioned by reason of the fit of the base 20 to the wall 70 of the bowl, and the only detail which a workman has to be particular about in attaching it is to drill the hole 32 in the bowl at the proper height. The hole 32 may vary somewhat in size without impairing the 75 function or affecting the positioning of the parts detrimentally.

Should it be desired to make an independent electrical circuit with the coil without using a ground, the base may have an extension 40 at one side, as indicated in Figure 4, in which an additional assembly and post screw 41 may be provided, a second opening 42 being required to be drilled in the bowl for installation of the device. The inner 85 end of the coil is engaged under the head of the bolt screw 41 and separate wires are led from the outer bolt parts 25 and 41, as before described.

The extension from the base may be either 90 lateral as indicated in Figure 4 or may be vertical as shown in Figure 5 at 45. In these latter installations, the workman need only assure the proper height for the first 95 hole drilled to receive the bolt 23—25 and then space the second hole properly therefrom in the desired direction.

After mounting the heater unit, it is desirable to make marks on the bowl and edge of the plate 13, which are to be alined when 100 the cam is assembled.

It will be apparent from the foregoing that I have provided a device adapted to be manufactured and marketed in a very compact and low-cost form which may be applied to the majority of carburetors of the ordinary kinds now in use, to improve their functioning, especially in cold weather, to enable easy starting, which proves difficult very often, as well as being adapted to enable the use of low grade fuel satisfactorily. 105

I claim:

1. In a carburetor including a circular reservoir and a float pivoted at one side of the bowl of a shape and having movement to lie inclined when at its lowermost position, an attachable heater element in the form of an elongated cylinder positioned beneath the float parallel to the pivot axis of the float adjacent its pivoted side, mounted within 120 and on the reservoir wall of a size to lie clear of the float when the float is in lowered position.

2. An attachable heater for carburetors comprising a cylindrical core having a 125 curved end face to fit the inner wall face of a carburetor bowl the axis of the core being at an acute angle to the chord of said end

face, an exposed wire helix wound on said core, a bolt extended axially through the core, said helix electrically joined thereto at the extremity of the core, said bolt projected through the curved end face, means to insulate the bolt from a bowl, and means including the bolt to clamp the core against a bowl through which the bolt may be inserted, and separate means to complete an electrical circuit to the other end of said helix.

In testimony whereof I affix my signature.

FRANK MIMICK.
